(57) **CLAIM**

We claim the ornamental design for door for display bins, as shown and described.

DESCRIPTION

FIG. 1 is a top, front, and right end perspective view of a door for display bins showing our new design;

FIG. 2 is a perspective view showing principally the top, rear and left end thereof;

FIG. 3 is a front elevational view thereof;

FIG. 4 is a top view thereof;

FIG. 5 is a right end elevational view thereof, it being understood that the left end elevational view is a mirror image of the right end elevational view;

FIG. 6 is a rear elevational view thereof;

FIG. 7 is a bottom view thereof;

FIG. 8 is a top, front, and right end perspective view of a second embodiment of a door for display bins showing our new design;

FIG. 9 is a perspective view showing principally the top, rear and left end thereof;

FIG. 10 is a front elevational view thereof;

FIG. 11 is a top view thereof;

FIG. 12 is a right end elevational view thereof, it being understood that the left end elevational view is a mirror image of the right end elevational view;

FIG. 13 is a rear elevational view thereof;

FIG. 14 is a bottom view thereof;

FIG. 15 is a top, front, and right end perspective view of a third embodiment of a door for display bins showing our new design;

FIG. 16 is a perspective view showing principally the top, rear and left end thereof;

FIG. 17 is a front elevational view thereof;

FIG. 18 is a top view thereof;

FIG. 19 is a right end elevational view thereof, it being understood that the left end elevational view is a mirror image of the right end elevational view;

FIG. 20 is a rear elevational view thereof;

FIG. 21 is a bottom view thereof;

FIG. 22 is a top, front, and right end perspective view of a fourth embodiment of a door for display bins showing our new design;

FIG. 23 is a perspective view showing principally the top, rear and left end thereof;

FIG. 24 is a front elevational view thereof;

FIG. 25 is a top view thereof;

FIG. 26 is a right end elevational view thereof, it being understood that the left end elevational view is a mirror image of the right end elevational view;

FIG. 27 is a rear elevational view thereof; and,

FIG. 28 is a bottom view thereof.

The broken line showing of the center of the door for display bins is for illustrative purposes only and forms no part of the claimed design. The door for display bins is shown in FIGS. 15-27 in a broken away condition for ease of illustration to indicate indeterminate length.
